UNITED STATES PATENT OFFICE

LUCIEN A. STEPHENS, OF ANGELS CAMP, CALIFORNIA

FIRE FIGHTING TOOL

Application filed May 18, 1931. Serial No. 538,385.

This invention relates to hand implements and especially to those necessary in fighting forest or brush fires; such as shovels and axes. In this State at least, on account of the climatic conditions, the mountainous areas become very dry during the summer months and fires are easily started. Since such areas are frequented by automobile campers who are apt to be ignorant and careless in their use of camp fires, matches and the like, it is a requirement of the Forest Service that each automobile shall carry a shovel and axe of sufficient size to be of practical use in fighting fires should the occasion arise.

The handles on the ordinary full-sized implements of this character are too long to be conveniently accommodated in an ordinary automobile, and the principal object of my invention therefore is to provide a handle structure formed of a number of separable sections so arranged that when in operation a full length of rigid handle for the implement is formed, but which can be instantly taken apart or separated, and yet will remain in connected relationship so that the sections of the handle cannot become lost. The handle therefore is ordinarily very compact and may be packed and carried in a small space.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective view of my improved handle structure as arranged in connection with a shovel and as ready for operation.

Fig. 2 is an enlarged fragmentary longitudinal section of the handle structure with the sections assembled.

Fig. 3 is a cross section on the line 3—3 of Fig. 2.

Fig. 4 is a side elevation of the handle structure with the sections dismounted from each other.

Fig. 5 is a longitudinal section of an implement blade as engaged with the handle to serve as a shovel.

Fig. 6 is a similar view showing the blade as engaged with the handle to form a hoe.

Fig. 7 is a fragmentary view of the handle structure as mounted in connection with an axe head.

Referring now more particularly to the characters of reference on the drawings, the handle structure comprises a number of tubular sections 1 which are of reduced size at one end as shown at 2 so as to telescopically fit into the end of an adjacent section. In order to prevent the turning of the sections relative to each other they are preferably provided with a ridge and groove arrangement along their telescoping portions, as shown in 3. Any other devices for serving the same purposes may of course be used instead.

The lowermost section, which is the one to which the implement itself is attached, is provided toward its upper end with a row of holes 4 in its opposite sides, through any matching pair of which a bolt 5 is removably passed. This bolt engages the adjacent end of a chain 6 or the like which extends through all the sections to the outer end of the uppermost one. At its upper end the chain is connected to the adjacent end of a bar 7 which at said end is provided with a cam surface 8 for engagement with the outer edge of the adjacent handle section. This bar is adapted to extend lengthwise along said section and at its opposite end is provided with a spring clip 9 adapted to partially surround and grip the section. If desired the bar when thus in place along the section may be countersunk in a groove, as shown in order that it will not project above the section, and so as to provide a smooth surface for engagement with the hand of the operator when using the implement.

By reason of this arrangement it will be seen that the chain and bar unit always prevents the sections from becoming definitely separated from each other even though they

are taken apart, since the chain at one end is connected to one section by means of the bolt 5 and at the other end of the bar, whose clip 9 is larger than the section and cannot pass therethrough. The length of this bar is sufficient to provide enough slack when outstretched and in alignment with the chain, for the disengagement of the telescoping portions of the section and the folding of the same in side by side relation, as shown in

Fig. 4. When the sections are assembled in rigid alignment, the bar projects for its full length beyond the upper section, and the cam surface 8 is then engaged with the edge of said section and the bar is folded over to extend along the section. This tightens the chain and holds the sections from separation. If the chain should stretch to any extent, the bolt 5 is shifted to another hole 4 to again give the chain the necessary tension.

At its lower end the lower handle section is given a wedge-shaped form, as shown at 10 to slidably and snugly fit in a socket 11 mounted on the upper surface of a blade 12. The blade is then in such relationship to the handle to serve as a shovel or spade. The sides of the socket and the portion 10 are provided with matching holes to receive a bolt or pin 13 to then maintain the parts against separation.

In order to enable the setting of the blade relative to the handle to be altered so that the blade may serve as a hoe, the upper surface of the socket and the blade below are provided with slots 14 whose dimensions are such as to receive the portion 10 in wedge engagement therewith, as shown in Fig. 6. In this case the same bolt 13 is used to prevent separation of the parts.

The same handle arrangement although somewhat shorter may also be applied to an axe, as shown in Fig. 7. In this case the lower handle section 1a is directly and rigidly secured to the axe head 15. Otherwise the construction and operation is the same as above described.

In marketing these implements it is my intention to sell the two types above described as a unit, since both are necessary to form a proper fire fighting equipment.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. An implement handle structure comprising separable handle sections adapted for

telescoping engagement at their adjacent ends, and means to then releasably tie all the sections together simultaneously.

2. An implement handle structure comprising separable handle sections adapted for telescoping engagement at their adjacent ends, a means common to all the sections to prevent longitudinal separation of the sections when once they are telescopingly engaged.

3. An implement handle structure comprising separable handle sections adapted for telescoping engagement at their adjacent ends, a means common to all the sections to prevent longitudinal separation of the sections when once they are telescopingly engaged while permitting them to be disengaged and separated from each other at will but only a predetermined distance.

4. An implement handle structure comprising separable handle sections adapted for telescoping engagement at their adjacent ends, a flexible element projecting through all said sections and secured at one end to the lowermost section, and means applied to the opposite end of the element for pulling and maintaining the same taut.

5. A structure as in claim 4, in which said means comprises a bar to one end of which said outer end of the element is attached and adapted when the sections are assembled to fold over and extend along the adjacent section, a cam surface formed on the end of the bar to which the element is attached and adapted for engagement with the end edge of the section to cause the element to be pulled taut by the folding over movement of the bar, and means on the outer end of the bar to releasably hold the bar flatly against the section.

6. An implement handle structure comprising separable handle sections adapted for telescoping engagement at their adjacent ends, a flexible element projecting through all said sections and secured at one end to the lowermost section, a bar to one end of which the other end of the element is attached, said bar being adapted, when the sections are assembled, to fold over and lie along the adjacent section and then hold the element taut, and a spring yoke on the outer end of the bar for straddling frictional engagement with the section.

7. A structure as in claim 6 in which the length of the bar is sufficient to enable the sections, when said bar is longitudinally aligned with the element, to be pulled apart from each other.

8. An implement handle structure comprising separable handle sections adapted for telescoping engagement at their adjacent ends, a flexible element projecting through all said sections and secured at one end to the lowermost section, a bar to one end of which the other end of the element is attached, said bar

being adapted, when the sections are assembled, to fold over and lie along the adjacent section and then hold the element taut, the length of the bar being greater than the combined length of the telescoping portions of the sections; and a member on the outer end of the bar adapted for releasable holding engagement with the adjacent section and incapable of passing through the same.

10 9. An implement comprising a handle, a wedge shaped portion on one end of the handle, a blade, a socket on the blade open to the back end of the same and shaped to receive said portion; the top of the socket and the blade below having slots to fit over the wedge shaped portion whereby the blade, when said portion is engaged with the slots, will be disposed at a different angle to the handle than when said portion engages the socket.

20 In testimony whereof I affix my signature.
